TOOL FOR SNAP RINGS

BACKGROUND OF THE INVENTION

The use of snap rings applied over shafts and in bores to prevent axial movement of parts thereon is well known in the art. While the specific structure of the tool used to apply snap rings may vary somewhat, basically these tools are comprised of a pair of levers pivotally interconnected intermediate their opposite ends having handle sections on one side of the pivot connection and jaw sections on the other side. The jaw sections are provided with some means for engaging the snap rings, and the jaws are disposed to pivot open or closed when the handles are squeezed together. Both the handles and the jaws are normally of a flat configuration and lie in common planes.

These tools are quite satisfactory for application of snap rings where the work is not required to be performed in close or restricted spaces. However, there are situations where there is very close quarters in which to work; i.e., there is some member which closely surrounds the shaft over which the snap rings are to be applied or removed, or a hollow member has an interior groove to receive a snap ring which acts as a retainer for a part such as a bearing. In such cases, the surrounding structure may provide obstacles which limit the space available and may prevent the jaws of the tool from entering the space between the surrounding structure and the shaft when opened or closed within said space.

Making the jaw sections of a smaller dimension is often not a feasible answer, since this will necessarily reduce their strength which may not be sufficient to perform the mechanical function.

SUMMARY OF THE INVENTION

According to the present invention, a snap ring applying tool is provided which is comprised of a pair of levers pivotally interconnected between their opposite ends, having handle sections on one side of the pivotal connection and jaw sections on the other side. Each of the jaw sections is disposed at an angle to the path of their pivotal travel to allow for the jaws to be utilized in a more confined space between a shaft and surrounding structure, while still maintaining the size and dimensions of the jaws for the required strength.

DESCRIPTION OF THE DRAWING

FIG. 1 is a plan view of one embodiment of a snap ring applying tool according to this invention;

FIG. 2 is a sectional view taken substantially along the plane designated by the line 2-2 of FIG. 1;

FIG. 3 is a sectional view taken substantially along the plane designated by the line 3-3 of FIG. 1;

FIG. 4 is a sectional view similar to FIG. 2 of another jaw configuration of a snap ring applying tool;

FIG. 5 is a longitudinal sectional view of a snap ring placed on a shaft in confined quarters; and

FIG. 6 is an end elevational view of the structure of FIG. 5 diagrammatically representing the improved ability of the tool of the present invention to operate in confined spaces.

DESCRIPTION OF THE PREFERRED EMBODIMENT

Referring now to the drawing, and for the present to FIG. 1, one embodiment of a tool for applying snap rings is shown. The tool includes a pair of identical levers 10 pivotally interconnected intermediate their opposite ends by a pivot pin 12. Each of the levers 10 has a handle section 14 and a jaw section 16. The ends of the jaw sections 16 are rounded as shown at 18 so that the tool can engage the loops on the snap ring. The levers 10 are not crossed so that when the handle sections 14 are squeezed together, the jaws will pivot open (as shown by the arrows in FIG. 1) expanding the engaged snap ring. The snap ring is then inserted over the shaft to which it is to be applied, and the handles are released. When the snap ring is in place, the tool can be removed. A similar tool envisions one

where the levers are crossed over each other to enable snap ring to be compressed.

As can be seen in FIG. 2, the jaw sections 16 are disposed at an angle with respect to their path of travel which is designated by the plane P. The angular disposition of the jaws 16 can be compared to the coplanar disposition of the handle sections 14 as shown by the sectional view in FIG. 3.

The benefit of having the jaws disposed at an angle is shown diagrammatically in FIGS. 5 and 6. In FIG. 5 a shaft is shown and designated generally as S on which a snap ring R is to be placed. Surrounding the shaft S is a concentric surrounding member M, and between the shaft S and the surrounding member M is a clearance space C. In FIG. 6 a pair of angularly disposed jaws according to this invention are shown in section in solid lines, expanded to insert a ring R. As can be seen, due to their angular disposition, the jaws have sufficient space to move into and out of the clearance space C without being obstructed by surrounding member M.

FIG. 6 shows a sectional view of conventional prior art jaws in dot-dash lines in their open position superimposed over the jaws of the present invention. Each of these jaws has the same size and shape as the jaws of the present invention shown in solid lines. However, these jaws are not angularly disposed with respect to the path of travel, but are coplanar therewith. As can be seen, this configuration of jaws, when expanded to insert the ring R, will be obstructed by the member M from entering into the clearance space C. Hence, these jaws will not be able to apply a ring to a shaft, nor will they be able to be inserted and expanded to remove a ring.

Thus, by providing jaws which are angularly disposed with respect to the path of travel, a tool can be provided which can operate in a much more confined space than prior art tools without sacrificing strength of the jaw members.

35 The exact degree of the angle of the jaws with respect to the path of travel will vary depending upon the size of ring which the tool is designed to apply. It will be appreciated that each size of tool can adequately operate only on a limited size of snap rings and shafts to which they are to be applied. In designing the jaw angle, it is preferable that the angle be such that the mid point of each of the jaws 16 be designed to be tangential with a shaft approximately at the middle of the range of sizes of shafts on which the tool is designed to operate. Thus, for smaller tools, the angle of the jaw with respect to the path of travel will be greater than on larger tools designed for use on larger size shafts.

40 Referring now to FIG. 4, a modified configuration of the jaw sections of the tool is shown and designated at 16'. In this configuration, the jaw sections are arcuate in configuration rather than flat or planar, as in the case of the jaws of FIGS. 1 and 2. This arcuate configuration allows for operation of the tool in even more restricted space than in the case of a flat or planar configuration. However, the range of sizes of shafts on which it can effectively be utilized is somewhat less than the range of sizes on which the tool of FIG. 1 can be used. This is because the arcuate configuration is less universal and more compatible with a specific size of a shaft. Also, this configuration is more expensive to manufacture.

45 While the invention has been described with a great deal of particularity, it is believed that the tool of this invention essentially comprises a pair of levers pivotally interconnected intermediate their opposite ends, the levers each having jaw portions on one side of the pivotal connection, which jaw portions are disposed at an angle with respect to the path of travel of the jaw.

I claim:

50 1. A tool for applying and removing snap rings to and from shafts where the shafts are encircled by a member to provide a restricted space comprising, a pair of levers connected between their opposite ends for pivotal movement, each of said levers having a handle section on one side of said pivotal connection and an elongated jaw section on the opposite side, said jaw sections being transversely inclined to the path of travel.

2. The invention as defined in claim 1 wherein said angularly disposed portions of said jaw sections are flat in cross section.

3. The invention as defined in claim 1 wherein said angularly disposed portions of said jaw sections are arcuate in cross section. 5
